UNITED STATES PATENT OFFICE.

GEORGE W. BLAIR, OF MISHAWAKA, INDIANA, ASSIGNOR TO MISHAWAKA RUBBER
AND WOOLEN MANUFACTURING COMPANY, OF MISHAWAKA, INDIANA, A COR-
PORATION OF INDIANA.

DESIGN FOR A SHOE SOLE.

Application filed March 2, 1929. Serial No. 30,298. Term of patent 14 years.

To all whom it may concern:

I, GEORGE W. BLAIR, a citizen of the United States, residing in Mishawaka, county of St. Joseph, and State of Indiana, have invented a new, original, and ornamental Design for a Shoe Sole, of which the following is a specification, reference being had to the accompanying drawing, forming a part thereof.

Fig. 1 is a plan view of a shoe sole showing my new design;

Fig. 2 is a longitudinal sectional view on line 2—2 of Fig. 1, and

Figs. 3 and 4 are transverse sectional views on the lines 3—3 and 4—4 respectively of Fig. 1.

I claim:

The ornamental design for a shoe sole as shown.

GEORGE W. BLAIR.
